CHRISTMAS DECORATION OR SIMILAR ARTICLE

Valda L. Pitzer, 7860 S. Causeway Blvd.,
St. Petersburg, Fla.

Filed Jan. 2, 1963, Ser. No. 33,033

Term of patent 14 years

(Cl. D29—1)

Fig. 1.

Fig. 3.

Fig. 2.

Fig. 4.

FIG. 1 is a side elevational view of a Christmas decoration showing my new design;

FIG. 2 is a top plan view thereof;

FIG. 3 is a fragmentary top perspective view thereof; and

FIG. 4 is a bottom plan view thereof.

The dominant features of the design reside in the portions shown in full lines.

I claim:

The ornamental design for a Christmas decoration or similar article, substantially as shown and described.
